METHOD OF SELECTIVELY ERADICATING
WEEDS FROM CARROT PLOTSMiller W. Swaney, Westfield, and Leo Z. Jasion,
Elizabeth, N. J., assignors to Standard Oil De-
velopment Company, a corporation of DelawareNo Drawing. Application August 2, 1947,
Serial No. 765,816

3 Claims. (Cl. 71—2.7)

1

This invention relates to improvements in materials for checking the growth of plants growing in cultivated ground to the detriment of the main crop.

An object of this invention is to provide material suitable for use as selective herbicides in the raising of vegetables. Another object of this invention is to provide a material which destroys weeds in vegetable beds and does not injure the vegetables.

We have found that aliphatic hydrocarbons in the normal C₁₀ to normal C₁₂ range are unusually selective in their herbicidal action on weeds and grasses in the presence of carrots, parsnips, celery, and similar vegetables. When these compounds are applied to beds of these vegetables the weeds are destroyed and the vegetables are unharmed.

Prior to this invention it had been assumed that the value of selective hydrocarbon herbicides for use on carrots lay in the aromatic compounds present. We have found that the aliphatic hydrocarbons in the beforementioned range are more selective in their herbicidal action and that the aromatic compounds actually harm useful plants.

The following examples will more clearly distinguish this invention.

Example 1

The following pure hydrocarbons were sprayed on potted coleus plants:

	Boiling Point	Action on Coleus blumei
Aromatics:		
Toluene	° F. 231	+++
Xylenes	280-290	+++
Ethylbenzene	277	+++
Isopropyl-benzene	306	+++
Isopropyl-toluene	348	+++
Methylmaphthalene	464-473	+++
Paraffins:		
n-Octane, C ₈ H ₁₈	258	+++
n-Decane, C ₁₀ H ₂₂	345	+++
n-Dodecane, C ₁₂ H ₂₆	422	+++
n-Tetradecane, C ₁₄ H ₃₀	488	+
n-Hexadecane, C ₁₆ H ₃₄	547	—
n-Octadecane, C ₁₈ H ₃₈	604	—
Olefins:		
n-Octene-1, C ₈ H ₁₆	251	+++
n-Octene-2, C ₈ H ₁₆	257	+++
Mixed 2, 4, 4-Trimethylpentenes-1 and -2	214-219	+++
n-Decene-1, C ₁₀ H ₂₀	342	+++
n-Dodecene-1, C ₁₂ H ₂₄	416	+++
n-Tetradecene-1, C ₁₄ H ₂₈	est. 480	++
n-Hexadecene-1, C ₁₆ H ₃₂	est. 540	—
n-Octadecene-1, C ₁₈ H ₃₆	est. 555	—

+++ = very toxic.
++ = moderately toxic.
+ = slightly toxic.
— = non-toxic.

2

It should be noted that only the open chain series show any degree of selectivity. The aromatic compounds were toxic in every test.

Example 2

Various pure hydrocarbons were applied to plantings of carrots and weeds including clover and cereal grasses under identical test conditions, i. e. spraying of the foliage from a low pressure sprayer at an atmospheric temperature of 80° F. The results were recorded at various intervals for several days after spraying. All plants were at the same stage of growth. In all cases the toxic symptoms did not change after the first day.

	Type of Hydrocarbon	Toxicity to Plants Indicated		
		Carrots	Clover	Grasses
20	Aromatics:			
	Toluene	+++	+++	+++
	Xylene	+++	+++	+++
	Isopropyl-toluene	+++	+++	+++
	Methylmaphthalene	+++	+++	+++
25	Olefins:			
	n-Octene-1	+	+++	+
	n-Octene-2	+++	+++	++
	n-Decene-1	—	+++	+++
	n-Dodecene-1	—	+++	+++
	n-Tetradecene-1	—	+++	+
	n-Hexadecene-1	—	++	—
	n-Octadecene-1	—	+	—
30	Paraffins:			
	N-Octane	+	+	+
	Iso-octane (2,2,4-trimethylpen-tane)	—	+	+
	n-Decane	—	+++	+++
	n-Dodecane	—	—	—
	n-Tetradecane	—	—	—
	n-Hexadecane	—	—	—
35	n-Octadecane	—	—	—

+++ = very toxic.
++ = moderately toxic.
+ = slightly toxic.
— = non-toxic.

40 The selective action is thus more strikingly brought out. Of the entire group, only n-decane, n-decene, n-dodecane and n-dodecene performed perfectly in killing all the plants except the carrots, which were not harmed in the least.

Example 3

45 In a field experiment, a carrot plot which was heavily infested with numerous farm weeds was sectioned up and different parts were sprayed at the rate of 100 gallons per acre with each of the following pure paraffins, n-decane, n-dodecane, and n-tetradecane, and the results observed, as follows:

50 n-Decane: carrots completely unharmed, grasses and weeds killed completely.

3

n-Dodecane: weeds and grasses killed but carrots were uninjured.
n-Tetradecane: carrots unharmed, but weeds and grasses incompletely eradicated.

Thus, in actual field practice, it is clear from these data that pure n-decane and n-dodecane performed completely selectively for eliminating weeds from carrots.

Example 4

A hydrocarbon fraction boiling in the range of 340-425° F. substantially the n-decene to n-dodecane range, was prepared by a hydrocarbon synthesis process from carbon monoxide and hydrogen in the presence of an iron type catalyst. This fraction composed of straight and branch chained alkanes and alkenes was used to spray a weedy carrot planting.

The result of the sprayings was that all weeds and grasses were completely eradicated and no harm at all was done to the carrots.

The advantages of this invention in scientific crop control are readily discernable.

The above examples are not to be construed as limiting either the method of application of our composition or the vegetables to which it may be applied.

We claim:

1. A method of selectively eradicating weeds from carrot plots which comprises distributing a composition consisting essentially of alkanes and alkenes boiling between 340° to 425° F. atmospheric and being free of aromatics so as to effect contact of the composition with the weeds.

2. A method of selectively eradicating weeds from carrot plots which comprises distributing a composition consisting essentially of alkanes boil-

ing between 340° to 425° F. atmospheric and being free of aromatics so as to effect contact of the composition with the weeds.

3. In a process for selectively eradicating weeds from carrot plots with herbicidal composition wherein the herbicidal composition is distributed into intimate contact with the weeds, the improvement which comprises using a composition consisting essentially of alkanes boiling between 340° to 425° F. atmospheric and being free of aromatics as the herbicidal composition.
